UNITED STATES PATENT OFFICE.

CLARENCE A. VEINOT, OF WATERVILLE, MAINE.

LOADING APPARATUS.

1,278,796.

Specification of Letters Patent. Patented Sept. 10, 1918.

Application filed August 8, 1917. Serial No. 185,038.

To all whom it may concern:

Be it known that I, CLARENCE A. VEINOT, a citizen of Nova Scotia, Dominion of Canada, residing at Waterville, Kennebec county, and State of Maine, have invented and discovered certain new and useful Improvements in Loading Apparatus, of which the following is a specification.

My said invention relates to loading apparatus and consists in the combinations and arrangements of elements hereinafter described and particularly set forth in the accompanying claims.

The invention has for its purpose to provide an apparatus adapted particularly for loading logs and the like, which may be readily transported from place to place and operated for lifting the logs from the ground to different elevations, and having means for adjustment, to the end that the apparatus may work with equal facility for elevating logs to the different higher levels.

The invention has for its further purpose to provide a log elevating apparatus constructed to work from either side of the material from a given position.

Another purpose of the invention is to produce an apparatus of this character, which may be set for operating in a substantially horizontal plane, when the elevators may work after the manner of the ordinary horizontal conveyers.

The invention further contemplates constructing an apparatus of this character and mounting the same on a motor-driven vehicle, to the end that the loader may be readily transported to the place for working, and there positioned with regard to the distribution of the material to be handled; and wherein the construction and arrangement of the whole is simple and may be readily controlled.

The invention is disclosed by way of illustration in the accompanying drawings,

45 wherein—

Figure 1 is a side elevational view thereof, Fig. 2 a top plan view of the same,

Fig. 3 an end elevational view,

Fig. 4 a transverse sectional view, taken 50 on the line 4—4 of Fig. 2.

Fig. 5 is a similar view, taken on the line 5—5 thereof,

Fig. 6 an enlarged detail view, in section, taken on the line 6—6 of Fig. 2, and showing 55 the turntable construction,

Fig. 7 an enlarged detail view, on the line 7—7 of Fig. 1, of the transmission gearing for the elevating mechanism and conveyer chains.

Fig. 8 a detail view of the transmission 60 and clutch control thereof, for the turn-table, and

Fig. 9 a top plan view of the tractor wheels and driving gear therefor.

Referring to the construction in further 65 detail and wherein like reference characters designate corresponding parts in the different figures, 9 indicates the body of any suitable vehicle or tractor, having steering wheels 10, tractor wheels 11, a driving engine 12, a suitable driving gear chain 13, a seat 14 for the operator, and a suitable control 15, after the manner shown. The loading apparatus is mounted on the body or frame 9 of the vehicle, hereinafter referred 70 to as the supporting structure; and motor 12 is utilized for operating the loading apparatus in the manner herein stated.

The loading apparatus consists of a revolvable platform or body 16 mounted on the 80 king-bolt 17 (see Fig. 6) and carrying a plurality of rollers 18 that travel on the annular track 19 secured to the supporting structure 9. Said turn-table 16 is mounted on the bearing block 20 that receives the king-bolt 85 17 by means of a number of ordinary fastening bolts 21, or in any other preferred manner.

A frame 22, comprising a plurality of parallel beams (see Figs. 1 and 3), is mounted to swing on the shaft 23 that is journaled in suitable bearing blocks 24 secured to the turn-table 16 along one side thereof, as shown. Said frame has journaled therein, on the respective ends of the beams 22, 90 a pair of shafts, 25 and 26; and a plurality of sprockets 27 are mounted on said shafts on the respective ends of each beam. An endless chain 28 is mounted to travel on each pair of sprockets, and said chains are provided with a number of laterally projecting arms 29 that serve to engage the logs or other material to be conveyed.

A supplemental conveyer, or loading device, is provided for coöoperating with the 105 main conveyer chains 28, and acts as a feeding conveyer or loader for said main conveyer chains. Said device consists of a pair of arms 30, that are swiveled on the shaft 26; and a sprocket 31, journaled in each of 110

said arms at the end, carries a chain 32 which rides over a similar sprocket 33 secured to the shaft 26 within the sides of the arm 30, as shown in Fig. 1. Said chains 32 are, in like manner, provided with projecting members 34 for engaging the articles carried.

The chain supporting frame 22 is adapted to be elevated in accordance with the height 10 to which the logs or other material are to be delivered; and said elevating device consists of a plurality of screw-threaded shafts 35 that are connected to suitable hangers 36, mounted on the shaft 37 that is journaled on 15 the frame bars 22. Said elevating shafts 35 are severally connected to be driven from the shaft 37 by the miter gears 38, whose pinions are mounted on the shafts 37 and 35, within said hangers 36. The connection 20 between the several shafts 35 and the platform 16 consists of threaded nuts 39 that are swivelly mounted in the brackets 40, secured to the under side of the turn-table 16, as shown (see Fig. 3).

25 The shaft 37, which directly drives the elevating shafts 35, is itself driven from the sprocket 43 through chain 41 that rides on sprocket 42 on said shaft 37, and miter gear 44 driven from the counter shaft 45 engages 30 and drives the sprocket 43. The shaft 45 is, in turn, driven from the main driving shaft 46, through either of the trains of gearing shown in Figs. 4 and 5, accordingly as the screw rods 35 are to be rotated in one direction or the other for raising or lowering 35 the frame. For rotating the shaft 45 in one direction, the pinion 47 on shaft 46 drives pinion 48 on shaft 49, and meshing with pinion 50; and said pinion 50 meshes with 40 pinion 51 mounted on the shaft 45. A clutch 52 serves for coupling the pinion 51 to rotate the shaft 45, when in one position. For rotating the shaft 45 in the opposite direction, the clutch 52 is moved to couple with 45 the pinion 53 on shaft 45, and said pinion 53 meshes with pinion 54 on shaft 49 (see Fig. 5). The pinion 54 is driven directly from pinion 55 on the counter shaft 46. The shaft 46 is connected to be driven from 50 the main driving shaft 56 of the engine, through the miter gear 57 (see Fig. 2).

The transmission gearing for operating the several carrying chains 28 consists of a chain 58, riding on sprocket wheels 59 and 60, on shafts 25 and 23 respectively. The sprocket 60 is keyed to the shaft 23 (see Fig. 7) and is driven from the counter shaft 61 through the miter gear 62; and shaft 61 is driven through the gear train 47, 48 and 60 50 (see Fig. 4). A clutch 63, slideable on the shaft 61, serves to connect the pinion 50 to rotate said shaft. The usual hand operating devices 64 and 65 are provided for shifting the clutch elements 52 and 63, 65 respectively. It will therefore be seen that

the several chains 28 of the loader are operated simultaneously from the shaft 25, driven through the gearing (58, 59, 60 and 62) and thereby the lower, or supplemental carrying chains 32 are operated.

70

The turn-table 16 is adapted to be rotated by a screw gear 66 on a shaft 67, and meshing with a worm wheel 68 that is formed in the bearing lock 20 of the turn-table. Said shaft 67 is driven from the engine 75 shaft 56 directly through the gear wheels 69 and 70, or indirectly thereby to obtain the reverse operation through the train 71, 72, and 73. A clutch 74 is shiftable to connect the shaft 67 to be driven from either 80 of the pinions 70 or 73, after the usual manner.

The duplicate gears 44 and 62 on the free end of the shaft 23 (as seen in Figs. 2 and 7) are adapted for engaging with the miter 85 gears 75 and 76 respectively, on the free ends of the shafts 45 and 61, in order that the working parts of the loader may be operated from either side of the vehicle.

A suitable detent device is provided for holding the turntable in either of its positions of operation, and said device consists of a spring pressed lever 77 adapted to engage in recesses 78 formed in the members 79, and adapted to be operated by a treadle 95 80 (see Figs. 1 and 3); located in proximity to the operator's seat 14, which serves for releasing the lever 77 and when the gearing is thrown in to rotate the turn-table.

The engine 12 is mounted on the forward 100 end of the frame 9 or directly over the steering wheels 10 which thereby carry virtually the entire load of the engine. The seat 14 for the driver is located substantially midway between the loading apparatus and 105 the motor to evenly distribute the weight and have the operator in the most advantageous position for running the car and for controlling and directing the operations of the loader.

The tractor wheels 11 of the vehicle are four in number (see Figs. 1 and 9) and are mounted respectively on the four axles 80 journaled in the two triangular frames 81. Said frames 81 are dependingly and swingingly mounted by the shaft 82 in the hangers 83 on the underside of the frame 9. (See Fig. 3). The wheels 11 are provided with suitable tires and are arranged in overlapping relation to "break joints" and thereby enable the wheels to bridge crevices and with the swinging frame (81), exert full tractor effort while traveling over uneven surfaces. The several wheels are connected to be positively driven from the motor by a suitable 125 driving gear comprising a chain 84 riding on sprockets 85 and connecting the first and third axles 80; a second chain 86 connecting sprockets 87 on the third and fourth axles; a third chain 88 connecting sprockets 130

89 on the second and fourth axles; and said third axle is directly driven through the transmission chain 13 from the motor.

It is obvious that those skilled in the art may vary the details of construction and arrangement of parts without departing from the spirit of my invention, and I do not therefore wish to be limited to such features except as may be required by the 10 claims.

Having thus described my said invention, what I claim as new and desire to secure by Letters Patent, is:

1. In a loading apparatus the combination 15 of a supporting structure, a shaft journaled on said structure, a frame pivotally mounted on said shaft, a plurality of screw rods carried by said pivoted frame and having threaded engagement with said supporting 20 structure for elevating said frame, shafts having sprockets journaled on said frame, endless carrying chains mounted to travel on said sprockets, a shaft journaled on the pivoted frame, gearing connections between 25 said frame shaft and the elevating screw rods, a driving connection between said frame pivot shaft and one of the sprocket carrying shafts, and means for operating said frame pivot shaft, substantially as set 30 forth.

2. In a loading apparatus, the combination 35 of a supporting structure, a body revolvably mounted on said structure, a shaft journaled on said body, a driven gear on said shaft, a frame pivotally mounted on said shaft, a plurality of screw rods swivelly mounted on the body and connected to said pivoted frame for elevating said frame, shafts having sprockets journaled on said 40 frame on either side thereof, endless carrying chains mounted to travel on said sprockets, a shaft journaled on said pivoted frame, gearing connections between said frame shaft and the elevating screw rods, a chain 45 driving connection between said driven gear and the frame shaft, a chain driving connection between said body shaft and one of the sprocket carrying shafts, and means for operating said body shaft, substantially as 50 set forth.

3. In a loading apparatus, the combination 55 of a supporting structure, a body revolvably mounted on said structure, a shaft journaled in the structure and geared to said body for rotating the same, a shaft journaled on said body at one side thereof, a frame pivotally mounted on said body shaft, a pair of driven gears on said body shaft, a plurality of screw rods swivelly 60 mounted on the body and connected to said pivoted frame for elevating said frame, shafts having sprockets journaled on said

frame on either side thereof, endless carrying chains mounted to travel on said sprockets, a shaft journaled on said pivoted frame, 65 gearing connections between said frame shaft and the elevating screw rods, a pair of driving chains connecting said driven gears and the frame shaft at either end thereof, a chain driving connection between said body 70 shaft and one of the sprocket carrying shafts, and a common means for operating said pair of driven gears, the body shaft and the shaft for moving the revoluble frame, substantially as set forth. 75

4. In a loading apparatus, the combination 80 of a supporting structure, a body revolvably mounted on said structure, a frame pivotally mounted on said body, screw rods for elevating the frame on its pivoted support, a shaft journaled on the pivoted frame, gear elements connecting said frame shaft with said screw rods, a shaft journaled on said body; a driven gear on said body shaft; driving connections between said body shaft 85 and the carrying chains, and said driven gear and the frame shaft; duplicate driven gear elements mounted on the respective ends of said body shaft, and a power transmission having duplicate driving gear elements for operating the carrying chains and elevating said frame from opposite sides of the supporting structure, substantially as set forth. 90

5. In a loading apparatus, the combination 95 of a supporting structure, a body revolvably mounted on said structure, a shaft journaled on said body, a driving gear on the body shaft, a frame pivotally mounted on said shaft, a plurality of screw rods swivelly mounted on the body and connected to said pivoted frame for elevating said frame, shafts having sprockets journaled on said frame at either side thereof, endless carrying chains mounted to travel on said sprockets, driving connections between said driven gear and the elevating screw rods, a driving connection between said body shaft and one of the sprocket carrying shafts, duplicate driven gear elements mounted on the respective ends of said body shaft, and a power transmission having duplicate driving gear elements for operating the carrying chains and elevating said frame from opposite sides of the supporting structure, substantially as 110 set forth. 115

In witness whereof, I hereunto set my hand and seal at Waterville, Maine, this 4th day of August, A. D. nineteen hundred and seventeen.

CLARENCE A. VEINOT, [L.S.]

Witnesses:

CARROLL N. PERKINS,
F. W. MANSON.
